UNITED STATES PATENT OFFICE.

HENRY C. NEER AND SAMUEL L. NEER, OF BRECKENRIDGE, ASSIGNEES OF
ONE-THIRD TO SAMUEL ROSENWALD, OF SPRINGFIELD, ILLINOIS.

CHECK ROWER AND MARKER.

SPECIFICATION forming part of Letters Patent No. 242,354, dated May 31, 1881.

Application filed March 14, 1881. (Model.)

To all whom it may concern:

Be it known that we, HENRY C. NEER and SAMUEL L. NEER, citizens of the United States, residents at Breckenridge, in the county of Sangamon and State of Illinois, have invented certain new and useful Improvements in Check Rowers and Markers; and we do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

15 Figure 1 is a perspective view of the device; Fig. 2, a detail.

This invention relates to improvements in check rowers and markers.

The invention consists in the construction hereinafter set forth.

In the annexed drawings, A is the pole of a planter, to which the device is attached by bolt B, which passes through cross-bar D above and C below.

25 Secured to the ends c c of cross-bar C are the forward upturned ends e e of shoes E E, whose right-angled rear ends, e' e', support a transverse bar, F, connected at the middle to the rear end of bar A, carrying at its ends f f the seed-boxes G G.

H is a slider-bar, having holes h h and turned-down ends h' h', which latter enter openings g g in the sides of the seed-boxes at the bottom. The tops of these boxes are slotted at g' g', and in these slits are located the ends i i of a bar, I, having in its body the slots i' i'. Through one of these slots passes a finger-rod, K, having its lower end, k, in the hole h below said slot, and connected above by a sleeve, k', to a rod, L.

40 Hinged to the ends d d of bar D are the ends m m of the side rails, which are twisted at m' m', carry a bar, N, near their ends m² m², and have said ends formed as eyes, in which is journaled the transverse shaft P. To the ends p p of this shaft are secured the markers Q, of any desired number, there being a sleeve, q, between these and eyes m². Formed at the ends

of any determined number of these markers are the pins q', extending at right angles outward from the arm q².

50 Formed upon one arm of each set of markers is the tapped lug R, the said lugs extending inwardly from the arms to which they are secured.

55 To the under side of the bar N, inside of eyes m², are secured eyes r, transverse to said bar. In these eyes are journaled the cranked levers S S, having an arm, s, extending outward under side rails, M, and another, s', upward behind bar N and shaft P. The ends of arm s' are connected by a loosely-jointed rod, T. Secured to this rod is a bracket, V, which extends backward over the seed-box-supporting frame, and has a series of holes, v, in which is 60 hooked the end of rod L.

To the front of bar N, just over bar A, is a hook, W, having the outer curved cam-surface, w, and the inner, w', forming a point, Z. This hook W serves the double purpose of 70 holding the markers down when in use by hooking under bar A, and keeping them up when not in use by bearing on the upper face of said bar.

75 What we claim is—

1. In a check rorer and marker, the combination, with the markers Q, having the tappets R, of the crank-levers S S, having arms s s', connected by the loosely-jointed rod T, provided with the perforated bracket V, the rod 80 L, finger-rod K, slotted bar I, and seed-slide H, substantially as and for the purposes set forth.

2. In a check rorer and marker, the combination, with the pole A and a pivoted or hinged 85 marker-frame, of the cam-hook W, pivoted centrally to the bar N of the marker-frame, substantially as and for the purposes set forth.

In testimony whereof we affix our signatures in presence of two witnesses.

HENRY C. NEER.
SAMUEL L. NEER.

Witnesses:

S. ROSENWALD,
L. H. BRADLEY.
